United States Patent Office

J. O'KANE, OF NEW YORK, N. Y., ASSIGNOR TO EDWARD H. HOTCHKISS,
OF BROOKLYN, NEW YORK.

Letters Patent No. 66,248, dated July 2, 1867; antedated June 20, 1867

IMPROVEMENT IN DRAW-PLATES.

The Schedule referred to in these Letters Patent and making part of the same.

TO ALL WHOM IT MAY CONCERN:

Be it known that I, J. O'KANE, of the city, county, and State of New York, have invented a new and useful Improvement in Draw-Plates for forming cylindrical tubes on the borders of sheet metal, to be applied to the making of hinges and other purposes, of which the following is a full, clear, and exact description, reference being had to the annexed drawings, making part of this specification, in which—

Figure 1 is a front view.

Figure 2 is a similar view illustrating the manner of turning in the edge of the metal.

Figure 3 is a transverse section of the tool.

Figure 4 represents a side or face view of a strip of sheet metal having one of its edges turned in by my invention.

Similar letters of reference indicate corresponding parts in all the figures.

The nature of my invention consists in providing a draw-plate with slits in connection with circular holes, said slits being designed for the reception of the flat portion of the metal, and the corresponding holes for forming tubes on the borders of same.

This draw-plate is made of a flat piece of steel, or other suitable metal, of the usual form of the draw-plate, perforated transversely with four conical holes a b c d , gradually decreasing in size from a to d , figs. 1, 2, and 3, d being of the required size of the tube. These holes are situated with their centres on a line parallel to one edge of the plate. Through the aforesaid edge, slits r r r r are cut down perpendicularly into the holes, parallel to the contiguous sides of the same, and just wide enough to admit the metal easily, and forming a tangent to the internal circular surfaces of the holes. A piece of metal is then fixed firmly to the slotted edge of the plate by suitable screws or bolts, thus closing the ends of the slits, as shown in the drawing. All sharp edges that would cut the metal in its passage are carefully rounded and smoothed away.

It will be seen that when constructed as above described the slits r r r r will all be of equal length, measured from a plane passing perpendicularly to, then through, the axes of their holes.

To use this tool, a strip of metal of the requisite width is tapered a little at one end and inserted into the largest opening r a ; at the side of the largest end of the orifice a , the tapering end projecting through the plate. It is then grasped by the drawing-dogs, and drawn through the plate in the usual manner of tube-drawing. That edge of the metal next the hole being forced against its curved side, is turned in or partially rolled up in the act of passing through, as shown at a , fig. 3. This process is repeated through the openings r b and r c successively, when the edge of the strip, by reason of the contracting sizes of the holes, will be almost closed against its side, as shown at c , fig. 3. A cylindrical mandrel of the proper size, and a little longer than the strip of metal, is next passed through the cavity formed by the folded border of the metal, one end being even with the tapered end of the blank, the other end projecting a little. The strip and mandrel are together inserted through the smallest opening r d , and drawn through as before, when the border will be rolled or turned around the mandrel into a cylindrical tube. A collar, exactly fitting the mandrel, is then slipped over its projecting end, which is passed through an opening in the plate, clasped by the dogs, and withdrawn. The collar, not allowing the metal to pass, strips it off the mandrel.

I do not confine my claim to the exact form of the tool given in the foregoing description, as the combination of the slit and circular hole can and should be modified somewhat, according to circumstances, the following among others, viz:

First. The number of openings r a r b r c r d in the plate, and their gradations in size, will depend upon the size of the tube, compared to the thickness or hardness of the metal. Thus, for a tube of the same size, hard metal will require more gradual folding than soft of equal thickness; thick metal more than thin of equal hardness, and vice versa. The number of holes, and their gradations in size, must vary accordingly.

Second. Though I prefer the circular holes slightly conical, as their action is thus more gradual on the border of the metal, they may be, nevertheless, cylindrical, the front ends being well countersunk, and all corners and edges being smoothed away.

Third. Instead of the holes and slits being in one plate, a series of plates may be used, one hole and slit in each plate.

Fourth. The holes may be made all of one size, and the gradations in the process secured by varying the lengths of the slits. When the tool is thus constructed the process begins through one of the longer slits, but a small portion of the blank being forced against the circular side of the hole; the operation is continued through the shorter slits, more and more being forced around the curve successively, with the same result as with a gradation in the holes and uniformity in the slits.

Fifth. Sometimes it is requisite that the flat part of the folded metal should form a secant to the tube instead of a tangent. In this case the tool is modified in form accordingly, the slits and holes forming, in connection, an opening corresponding to the requisite form of the folded piece, the action of the tool and the manner of using being essentially the same.

What I claim as new, and desire to secure by Letters Patent, is—

The construction of a draw-plate with a communicating slit, *r*, arranged with reference to each hole, substantially as and for the purpose herein specified.

J. O'KANE.
